UNITED STATES PATENT OFFICE.

ARTHUR FRANCIS BERRY, OF EALING, ENGLAND.

CURRENT-INDICATOR.

1,305,514.

Specification of Letters Patent.

Patented June 3, 1919.

Application filed May 12, 1917. Serial No. 168,296.

To all whom it may concern:

Be it known that I, ARTHUR FRANCIS BERRY, a subject of the King of Great Britain and Ireland, residing at Ealing, in the county of Middlesex, England, have invented Improvements in or Relating to Current-Indicators, of which the following is a specification.

This invention has reference to electric current indicators designed to serve as fuses, and it has for its object to provide improved constructions of electric current indicators suitable for electric circuits of various kinds but particularly those intended for cooking, heating and like purposes, so that it can be readily determined at a glance whether the circuit with which the current indicator is associated is in action or not.

A current indicator device according to the invention is so constructed, that when in ordinary use, a portion thereof intermediate of its ends is caused to become luminous by the current passing therethrough while its end portions, for connection to terminals, remain cooler and relatively non-luminous. For this purpose a resistance conductor such as a resistance wire or strip made of small gage and of a metal or alloy, such for example as nickel chromium alloy, that is not readily fusible and which when heated to redness by an electric current, becomes coated with a protective insulating film of oxid, is so wound, bent or otherwise formed as to constitute one or more concentrated or localized intermediate portions in which heat, due to the passage of an electric current of predetermined safe value therethrough, is allowed to develop sufficiently to cause it or them to become luminous or glow while the remaining portions of the conductor wire are left sufficiently cool to prevent them becoming red hot and luminous. To assist in the production of a glowing heat in the said concentrated portion or portions of resistance conductor, such portion, or each of them when two or more are provided, may, when in use be shielded to a greater or less extent against the cooling action of surrounding air, as by shielding means on the conductor or the current indicator block or carrier, while the remaining portions of the current indicator are left freely exposed to the cooling action of air so as to be prevented from becoming luminous.

Current indicators according to the invention can be variously constructed.

In the accompanying illustrative drawings, Figure 1 shows partly in side elevation and partly in vertical section and with part of the current indicator block broken away, 60 a current indicator fuse constructed according to the invention. Fig. 2 is a plan of the current indicator with the cover shown in Fig. 1 removed. Fig. 3 is a view of the current indicator alone drawn to a still 65 larger scale. Figs. 4 and 5 are similar views to Fig. 1, showing modified constructions. Figs. 6, 7, 8 and 9 are views showing other forms of current indicators according to the invention. Figs. 10 and 11 are two views 70 showing another construction of current indicator according to the invention. The current indicators are shown to an enlarged scale for the sake of clearness.

According to the construction shown in 75 Figs. 1, 2 and 3, the central portion of a length of fine wire or strip *a* of resistance metal or alloy such as referred to, is coiled, as for instance around a pin or former, to form as shown, a small helix or spiral *a*¹ 80 comprising a few convolutions insulated from each other but arranged near together and of small diameter, say for example of the order of about one sixteenth or one eighth of an inch, the end portions of the 85 wire or strip (hereinafter referred to as wire) being left straight, except it may be the extreme end portions which may be coiled to form eyes, to fit over terminal screws, or which, as shown, may be simply 90 fixed in terminals *b* fixed to a block or carrier *c* of ordinary refractory insulating material such as porcelain. The block *c* may, as shown, be formed with a concave part *d* adapted to shield the central coiled portion 95 *a*¹ of the current indicator to some extent from air currents and to reflect radiant heat received from such central portion back on to the same and so assist in its being raised to and maintained at a temperature at which 100 it will become luminous or glow. Or, for a like purpose, the block *c* may, as shown in Fig. 4, be provided with a cup-like part *e* in which the coiled portion *a*¹ of the current indicator is placed and which has oppositely arranged slits or passages *e*¹ through which the end or side portions of the wire *a* extend. To further shield the coiled portion 105 *a*¹ of the current indicator, the cup-like part *e* may, as shown, be provided with a cap *e*² 110 formed with a viewing aperture *e*³.

Fig. 5 shows a current indicator provided

with two coiled portions a^1 each adapted to glow as described, when in use.

Fig. 6 shows a current indicator comprising a length of resistance wire a the central portion a^1 of which, for a short length, is made, as by drawing, of reduced diameter, to form the localized portion that will glow when the circuit of the heating or other device of which the fuse forms part, is in action.

Fig. 7 shows a current indicator comprising a length of strip metal the central portion a^1 of which is reduced in width, as by stamping or cutting, to form the localized portion that will glow under the circumstances mentioned.

The concentrated or localized portion a^1 of the current indicator can be shaped to give a dot or dash of redness for the required indication when traversed by a predetermined safe working current.

If desired, the whole current indicator, when mounted, may, as shown in Figs. 1 and 4, be provided with a protective cover f having an aperture at g through which the coiled portion a^1 of the current indicator can be seen when glowing. Such a cover serves to protect the current indicator from external air currents, particularly if the block e be not provided with a cup-like part e for shielding the part a^1 .

When current indicators of the kind described are used with heating devices of high and low heating value arranged in proximity to one another, the apertures g in the covers f of the separate current indicators may be fitted with glass or mica windows of different colors, or be otherwise adapted, to indicate for example high and low heating values so that it can be readily seen when a heating device of high or low heating value is in use. Or the localized or glow portions a^1 of the current indicator may be shaped to give such indication, as illustrated for instance in Figs. 8 and 9, where resistance strip material is shaped, as by stamping, to form the glow portion a^1 in the shape of the letters **H** and **L** respectively to indicate high and low.

The current indicator blocks are shown in Figs. 1, 4 and 5 provided with plug connections h connected to the terminals b .

According to the construction shown in Figs. 10 and 11 the current indicator is built up of very fine wire a of the kind referred to, by winding the wire, with the aid of a former, until a suitable number of strands or loops of convenient length are assembled as shown in Fig. 10 to suit the current to be carried. The requisite concentration of the intermediate or central portion of the fuse thus produced may then be obtained by twisting as a whole the central portion of the group of strands that are disposed parallel to one another in the act of wind-

ing. In this way there can be obtained a current indicator having, as shown in Fig. 11, a concentrated portion a^1 the parts of which, being covered with a thin film of oxid when heated to redness previous to twisting, 70 that is to say, in the course of manufacture, will be insulated from each other, and two enlarged end portions a^2 each composed of a number of turns of wire that may be spaced apart as shown, to allow of air entering 75 freely between them to keep them cool. The end portions a^2 serve for attachment to fuse terminals on a fuse block.

Current indicators constructed as described, have a very small voltage drop, a 80 very small energy consumption and a small heating capacity which is localized.

What I claim is:—

1. An electric current indicator comprising a conductor having between its end portions a localized glow portion forming only a comparatively small part of the length of the conductor and adapted when traversed by an electric current, to glow, while its end portions remain cooler and relatively non-luminous, and means arranged behind and in proximity to said glow portion and having its front surface adapted to throw forward radiant energy received from said glow portion and concentrate it on said glow 95 portion for the purpose set forth.

2. An electric current indicator comprising a conductor having between its end portions a localized bent portion forming a small closely spaced bent mass of conductor 100 constituting only a small part of the total length of the conductor and adapted to glow and serve as a current indicator when traversed by an electric current, said conductor being formed of metallic resistance material 105 having a high melting point and having thereon a protective insulating film of oxid, and means arranged behind and in proximity to said glow portion and having its front surface adapted to throw forward radiant 110 energy received from said glow portion and concentrate it on said glow portion for the purpose set forth.

3. An electric current indicator comprising a conductor made of oxidizable metallic 115 resistance material and having between its ends a portion thereof bent to a convoluted shape so as to constitute a minute concentrated portion of conductor of a length forming only a small fraction of the total 120 length of the conductor and adapted to admit of heat developing therein sufficiently to cause it to become luminous when traversed by an electric current while the remaining end portions of the conductor will remain 125 sufficiently cool to prevent them becoming red hot, said convoluted portion having a film of metallic oxid thereon, and a refractory body arranged in proximity to and behind said convoluted mass and having a 130

concave approximately spherical front surface adapted to throw forward radiant energy received from said mass and concentrate it on said mass for the purpose set forth.

4. An electric current indicator comprising a conductor having a small portion of its length adapted to form a bead or spot of light while its remaining and longer end portions remain relatively non-luminous when traversed by an electric current and a refractory body arranged behind and in close proximity to the said portion of conductor adapted to form the bead or spot of light and having a concave approximately spherical front surface adapted to throw forward energy received from said luminous portion of conductor and concentrate it on said luminous portion of conductor.

5. An electric current indicator comprising a conductor formed of metallic resistance wire and having between its end portions, a coiled portion the convolutions of which are near together and each provided with a film of metallic oxid that separates it sidewise from adjacent convolutions, said coiled portion forming a concentrated glow device constituting only a small fraction of the length of the current indicator, and a refractory body arranged behind and in proximity to said coiled portion of said conductor and having on its front side a concave approximately spherical surface adapted to throw forward, heat and light energy received from said coiled portion of conductor and concentrate said energy on such portion of conductor for the purpose set forth.

6. An electric current indicator having a small portion of its length between its end portions adapted to glow and form a bead

or spot of light when traversed by an electric current while its remaining and longer end portions remain relatively non-luminous and means adapted to shield said glow portion to some extent against loss of heat while leaving the remaining end portions of said current indicator unprotected against loss of heat.

7. An electric current indicator having a portion thereof adapted to form when in use, a localized luminous portion to serve as a current indicator, and a cup like part in which the localized luminous portion of the current indicator is placed and through side portions of which the cooler end portions of the current indicator pass.

8. An electric current indicator having a portion thereof adapted to form when in use, a localized luminous portion to serve as a current indicator, a cup like part in which the localized luminous portion is placed and through side portions of which the cooler end portions of the current indicator pass and a cap secured over the cup like part and provided with a viewing aperture.

9. An electric current indicator comprising a base, terminals carried thereby, a length of conductor connected between said terminals and having a portion thereof adapted to form, when in use, a localized glow portion, a shield surrounding said glow portion and having a view aperture therein and a cover inclosing said current indicator and having a view aperture therein opposite that in said shield.

Signed at London, England, this 18th day of April 1917.

ARTHUR FRANCIS BERRY.
